MICROPHONE

Jacob Louis Snoek, Eindhoven, Netherlands, assignor to Radio Corporation of America, a corporation of Delaware

Application March 28, 1932, Serial No. 601,522
In Germany April 24, 1931

4 Claims. (Cl. 179—123)

This invention relates to a device used in microphones comprising a plurality of diaphragms. Microphones of this type are possessed of a greater sensitiveness than microphones comprising a single diaphragm. In most cases, however, this greater sensitiveness can only partly be profited by on account of the position of the diaphragms with respect to each other. If, for example, the sound waves catch the microphone from one point in space and the surface of one of the diaphragms is given the most favourable position with respect to the sound source then the other diaphragms will in general occupy a less favourable position, thus producing a "shadow effect" in the reception of the different frequencies or that the high frequency waves catch the diaphragm occupying the most favourable position but not or at least to a very lower extent the other diaphragms. This is due to the fact that in contradistinction to the low frequency waves the high frequency waves in view of their small wave length cannot flow around the walls of the microphone. Owing to this deformations in the reception occur. It has been supposed hereinbefore that the microphones are furnished with flat diaphragms. However, it will be appreciated that the above reasoning also holds good for microphones comprising diaphragms of other shape, for example, slightly curved diaphragms. For convenience's sake flat diaphragms will be considered hereinafter.

If the microphone is given a position different from that just referred to with respect to the sound source then this deformation in the reception remains to a greater or lesser extent. In case the surfaces of the diaphragms extend in parallel to each other and into the direction of the sound source, then the position of the diaphragms is equivalent, it is true, but not the most favourable for the reception.

The drawback of the shadow effect might be reduced by resorting to the known construction in which the sound waves are lead to the microphone through a mouth piece branched into two tubular members debouching in front of the diaphragms. However, this construction has the drawback that there occur resonance phenomena due to the funnel—or hornshape of the said members, which phenomena entail at the same time a favouring of some frequencies and consequently also give rise to deformation.

In order to avoid the said shadow effect the device according to the invention comprises two or more flat or substantially flat surfaces which may be given different positions and consist of

a sound reflecting material, for example, metal, said surfaces being placed in the vicinity of the diaphragms. The surfaces may be pivotally fixed to the housing of the microphone. However, they may also be placed separately beside the microphone. By means of this construction it is possible to place the microphone and the diaphragm surfaces in the direction of the sound source, since the surfaces according to the invention may be given such a position with respect to the sound source and the diaphragms that both the high and the low frequencies affect the diaphragms as efficiently as possible. In this manner the total sensitiveness of the microphone is increased up to the maximum value without affecting the quality.

If the sound source is concentrated in a single point of space, then in case of using a microphone comprising two diaphragms placed on either side of the microphone and in parallel to each other, a suitable form of construction is obtained, for example, if a plate is pivotally fixed to the circumference of the housing of the microphone in the vicinity of each diaphragm. Of course, the microphone is placed in such a manner that the aperture between the reflecting surfaces and the diaphragms is turned to the sound source. In addition to the desired acoustic effect obtained, this form of construction has the advantage that the plates may be turned inwards in such a manner that they are placed in parallel to the diaphragms, thus protecting the latter against mechanical damaging when the microphone is not used.

Preferably, the angle between the diaphragms and the plates is 45° whilst the surface of the plates is so chosen that the projections of the plates on the diaphragms entirely cover the latter in this position.

The invention will be more clearly understood by reference to the accompanying drawing, representing by way of example, one embodiment thereof.

Fig. 1 is a section of a microphone according to the invention and

Fig. 2 is a perspective view of same.

In Fig. 1, 1 is the section of a rectangular wall consisting of insulating material on either side of which two recesses 2 and 3 are provided which serve as carbon chambers and are consequently filled with carbon granules. Furthermore these chambers contain the rectangular electrodes 4 and 5 of the microphone which are shown in plan view on the drawing. Both chambers commun-

cate with each other through an aperture in the wall 1 (not represented). The chambers are shut off by the diaphragms 6 and 7 respectively whose rim is clamped between the wall 1 and the ridges 8 and 9 fixed to the wall by means of bolts 10.

5 At 11 and 12 two plates 13 and 14 are pivotally fixed on one side of the circumference of the wall 1. In the drawing the angle between diaphragms and plates is 45° but may also have another value. Furthermore it is not imperative that the angles have the same value. By the arrows shown in Fig. 1 is indicated that sound waves catching the microphone in the direction 15 are reflected on the membranes in the direction 16. It will be obvious that in this way both low and high frequency waves catching the reflecting surfaces 13 and 14 from the direction 15 will be received as efficiently as possible by the microphone.

10 15 I claim:

20 1. A sound translating device comprising a plurality of diaphragms, in which a plurality of substantially flat surfaces which may be given different angular positions are placed in the vicinity

of at least one diaphragm, said surfaces consisting of a sound reflecting material.

2. A translating device as claimed in claim 1 for use as a microphone in which two diaphragms are placed in parallel to each other on either side of the microphone and in which a sound reflecting plate is pivotally fixed to the outer edge of the housing of the microphone in the vicinity of each diaphragm.

3. A device as claimed in claim 1, in which the angle between diaphragms and plates is substantially 45° and in which the surface of the plates is such that the projection of the plates on the diaphragms covers the surface of the diaphragms.

4. A sound transition device comprising a rectangular wall of insulating material forming a chamber to retain carbon granulars, a plurality of diaphragms mounted on each side of said wall, and a plurality of adjustable plates having surfaces of sound reflecting material pivotally fixed to one side of the circumference of said wall so as to open in a book-like manner.
